UNITED STATES PATENT OFFICE.

GEORGE MARSHALL, OF FREMONT, NEBRASKA.

STEAM-BOILER.

No. 811,236.

Specification of Letters Patent.

Patented Jan. 30, 1906.

Application filed September 5, 1905. Serial No. 276,992.

To all whom it may concern:

Be it known that I, GEORGE MARSHALL, a citizen of the United States, residing at Fremont, in the county of Dodge and State of Nebraska, have invented certain new and useful Improvements in Steam-Boilers, of which the following is a specification.

My invention relates to steam-boilers of the class in which fire-tubes which pass horizontally through the boiler are connected at their ends to the boiler-heads; and the principal object of my invention is to provide a strong and durable connection between the tubes and boiler-heads to protect these joints and to prevent leakage. In my application for patent, filed June 12, 1905, Serial No. 264,827, I have shown a boiler constructed to carry out these general objects; but by my present improvements I simplify the construction of some of the parts, make them more efficient, and more easily put together and taken apart.

The ends of the fire-tubes in my improved boiler are connected to the boiler-heads in the usual way, and to the rear head next the fire-box I attach a protecting-plate of improved construction. This plate is preferably made in four sections, so that it may be more easily applied to the boiler and in order that only one section need be taken down when repairing some defective flues. Each section of the plate is formed with holes registering with the tubes and with annular flanges around the holes adapted to register with and be calked to the annular beaded ends of the tubes outside the tube-sheet. The plate is bolted to the tube-sheet and may, if desired, be calked all around its edge. Preferably the plate is made in four sections, as above stated, and the joints of the sections are covered by metallic strips, which are also bolted to the tube-sheet and are preferably calked to the plates. As an additional protection I cover the plate with a protecting-wall constructed of sectional tiles so formed as to be easily put together and taken apart and which may be readily secured to the protecting-plate or detached therefrom. Preferably the protecting-wall is made in four sections and formed with flanges that cover the edges of the plate. The wall has holes registering with the holes in the plate and the tubes, and it has recesses to receive some of the bolts which attach the plate to the tube-sheet. These bolts are employed for holding the protecting-wall in place.

In the accompanying drawings, Figure 1

shows a vertical section of a portion of a steam-boiler with my improvements applied, the section being taken on the line 1 1 of Fig. 2. Fig. 2 is an end elevation thereof. Fig. 60 3 shows an end elevation with one section of the protecting-wall removed. Fig. 4 is a perspective view looking at the under side of one of the wall-sections. Fig. 5 is a detail view, on an enlarged scale, looking at the front of a portion of one of the protecting-plates. Fig. 65 6 shows a section on the line 6 6 of Fig. 5. Fig. 7 is an enlarged sectional view showing the connections between the tube-sheet, a tube, and the protecting-plate. Fig. 8 is a perspective view of one of the strips employed for connecting the sections of the protecting-plate to the tube-sheet. Fig. 9 is a front elevation of the protecting-plate with the connecting-strips applied. Fig. 10 is an enlarged sectional view showing the manner of connecting the tube-sheet, the protecting-plate, and the protecting-wall. Fig. 11 is a perspective view of one of the filling-rings.

The boiler A, fire-tubes B, and boiler-head 80 or tube-sheet C are of usual construction. The fire-tubes have their ends projecting through the head C and spun over or beaded, as indicated at x. The boiler-head may be calked at c around the tubes, as indicated in Fig. 7. While this connection is quite efficient, it often permits leakage, owing to expansion and contraction of metal next to the fire-box. In order to prevent this, I employ a protecting-plate D, which is made of comparatively thick metal and is secured by bolts E to the boiler-head. Preferably I make this plate in four sections, as indicated in Fig. 9, in order that it may be more conveniently applied and that when it is necessary to repair any of the joints of the tubes of the boiler-head only a portion of the plate need be removed. This plate may be calked all around its edge, and preferably the joints between the plates are covered by strips F, 85 which are applied as indicated in Fig. 9, being bolted to the boiler-head and held firmly against the plate-sections. These strips may be calked to the plate in the manner indicated at f in Fig. 10. The plate-sections 90 are formed with holes or openings G, registering with the holes in the tube-sheet. Each of these holes is formed with an annular flange g, which produces an annular recess g', adapted to fit over the beaded end x of the 95 tube in the manner indicated in Fig. 7. It will be observed that the outer end of the

hole G is somewhat larger than the hole in the tube-sheet or boiler-head and that the metal to form the flange g is turned down from the metal taken from the plate to form 5 the enlarged opening. The recess g' is made to approximately fit the beaded end of the tube; but as a close fit cannot always be obtained the flange g is calked down into close engagement with the bead of the tube by a 10 suitable tool. In this way a secure connection is effected and danger of leakage avoided. After the flanges g have been made to engage 15 the beaded ends of the tubes filling-rings M are placed in the recesses in front of the flanges. This protecting-plate is very efficient without the use of further protecting means; but I prefer to employ also a protecting-wall H, composed of fire-brick or tile. This protecting-wall is made in sections, so 20 that it may be easily set up or taken apart, and it is formed with flanges h, that overlap the edges of the protecting-plate. Each section of the protecting-wall is formed with a number of holes I, registering with the holes 25 in the protecting-plate and the tubes and it is formed also with recesses J to receive the heads of the bolts that secure the plate to the boiler-head. Some of the bolts E are extended in the manner indicated in Fig. 10 30 and pass into recesses K in the outer faces of the wall-sections. These recesses receive nuts k. In this manner the wall-sections are held firmly in place. After they are set up the recesses K may be filled with paste or 35 mortar, and the joints between the sections may be filled with paste or mortar, so that the front face of the wall will appear without joint, as indicated in Fig. 2. Preferably the protecting-wall presses closely against the 40 filling-rings M and holds them against the flanges g.

A steam-boiler thus constructed is strong and durable and will stand great heat without deterioration or leakage, and the parts may be easily assembled or taken apart. 45

I claim as my invention—

1. The combination of a boiler-head, fire-tubes projecting through the head and beaded on their outer ends, a protecting-plate having holes registering with the tubes which 50 is formed with flanges containing grooves to receive the beaded ends of the tubes.

2. The combination of a boiler-head, fire-tubes attached thereto, a protecting-plate made in sections having holes registering 55 with the tubes and secured to the boiler-head, and metallic strips covering the joints between the sections in the front face of the plate.

3. The combination of a steam-boiler, a 60 protecting-plate attached to one of the boiler-heads, a protecting-wall covering the outer face of the protecting-plate and having recesses in its inner and outer faces, headed bolts securing the protecting-plate to the 65 boiler-head having their heads in the inner recesses of the protecting-plate, and headed bolts securing the protecting-wall to the protecting-plate, having nuts arranged in the recesses in the outer face of the protecting-wall. 70

4. The combination of a boiler-head, fire-tubes projecting through the boiler-head and beaded on their outer ends, a protecting-plate having holes registering with the tubes, flanges around these holes engaging the beads 75 and filling-rings in front of the flanges.

In testimony whereof I have hereunto subscribed my name.

GEORGE MARSHALL.
